UNITED STATES PATENT OFFICE.

GLENN H. CURTISS, OF HAMMONDSPORT, NEW YORK, ASSIGNOR TO THE CURTISS MOTOR COMPANY, OF HAMMONDSPORT, NEW YORK, A CORPORATION OF NEW YORK.

BOAT-HULL.

1,223,318.

Specification of Letters Patent. Patented Apr. 17, 1917.

Original application filed September 6, 1912, Serial No. 718,840. Divided and application filed June 4, 1913, Serial No. 771,646. Divided and this application filed June 7, 1915. Serial No. 32,653.

To all whom it may concern:

Be it known that I, GLENN H. CURTISS, a citizen of the United States, and a resident of Hammondsport, in the county of 5 Steuben and State of New York, have invented certain new and useful Improvements in Boat-Hulls, of which the following is a specification.

My invention relates to boat hulls. Boat 10 hulls made according to my invention are particularly useful in hydro-aero-machines, and the principal object of the invention is to provide a durable and efficient boat hull so arranged and constructed as to be capable 15 of readily supporting a hydro-aero-machine on the water and enabling it to readily gain flying speed on the water and fly from the water into the air.

The present application is a division of 20 one previously filed by me on June 4, 1913, Serial Number 771,646, for flying boat, which in turn was a division of an application filed by me on September 6, 1912, Serial Number 718,840, for flying boat, and since patented as Patent Number 1,085,575, granted January 27, 1914.

The invention consists in the novel features hereinafter shown and described and more particularly pointed out in the appended 30 claims.

Further objects and advantages of my invention will more fully appear and the invention will be more fully understood from the following description taken in connection 35 with the accompanying drawings illustrating a hydro-aero-machine having a boat embodying the preferred form of the invention, and in which—

Figure 1 is a side elevation of the entire 40 machine;

Fig. 2 is a front elevation of the boat with the air planes broken away;

Fig. 3 is a plan of the boat with the supporting planes removed; and

Fig. 4 is a detail cross-section through 45 the boat along line 4—4 of Fig. 3.

Referring more particularly to the drawings, there is shown a boat 1 of sufficient buoyancy for supporting the entire machine 50 upon the water and having mounted above the same one or more supporting planes 2 and 3 connected by the usual forward and rear struts 4, 5 forming an aeroplane. These supporting planes 2 and 3 are arranged in

lifting relation to the boat when floating 55 on the water, and in the preferred form of the invention shown the planes are located with the center of gravity lying intermediate their forward and rear edges. The center of gravity of the machine, without the 60 aviators aboard, is indicated by the dot *c, g*, somewhat forward of the step. Of course with the aviator or aviators aboard, the center of gravity is shifted somewhat forward and downward from the point *c, g*. The 65 machine is provided with suitable driving means consisting of engine 6 and air propeller 7 of sufficient capacity to drive the machine at such speed as to enable the air planes to lift said machine clear of the water 70 in flight.

The boat 1 is of seaworthy construction for travel on the water and contains therein, preferably at its forward part, the cockpit 8 with the operator's seat and other controls more particularly described hereinafter, and extends as shown from the front to the rear of the entire machine to serve as the fuselage therefor. To facilitate the breaking away of the boat from the water 75 when the machine rises in flight, the bottom of the boat is flat as shown in Fig. 4, and is provided with a rearwardly facing step 9 (see Fig. 1) at a point approximately below its center of gravity. The bottom of 80 the boat inclines from this step 9 upwardly toward the front at 10, and also upwardly at 11 toward the rear. The stern 12 of the boat looking from above is preferably pointed as shown in Fig. 3, while the bow 13 of 85 the boat is broad with a scow-like prow.

The upper deck 15 of the boat also preferably inclines from the center downwardly toward the rear, and at the forward portion the upper deck is preferably stepped to form 90 the cockpit 8 for the operator. The hull of the boat is formed of rigid material such as wood or metal to withstand the water pressure, but above its forward part is provided with a hood 16 forming a false bow 95 of streamline entry and continuing the streamlines of decking 15, of fragile material such as canvas, supported on slat ribs 17 of thin wood or other easily yielding material to form the cockpit 8 around the operator's seat. The cockpit floor or deck forms a pontoon wall. The hood 16 acts as a spray shield and its fragile nature allows 100 105

it to collapse and prevent injury to the operator if he should be thrown violently forward due to any accident or sudden stopping of the machine. Behind the operator's seat may be carried the main fuel tank 18 for the engine 6, which preferably communicates with an upper auxiliary fuel tank 19 carried adjacent said engine through pipe 20 and pump 21 operated by said engine. The boat may also be provided with suitable water-tight compartments (not shown) behind the storage tank for increased buoyancy.

It will be observed that the forward part of the boat is provided with a scow bow, namely, an overhanging bow with a fairly broad bottom surface, and that the bottom of the forward portion of the boat is in the form of an effective hydroplaning surface extending from the nose of the scow bow downwardly and rearwardly and thence rearwardly and more horizontally terminating at the rearwardly facing step. This hydroplaning surface as shown in the drawings, extends the full width of the boat between the submerged sides of the boat extending along the length of this surface to get the maximum hydroplaning width for a given shaped boat, and the bottom of the boat extending along the tail portion is in the form of a reverse hydroplaning surface. By "reverse hydroplaning surface" I mean a surface which is inclined upwardly and rearwardly, permitting the stern to be tilted down (and thereby having just the opposite effect from a hydroplaning surface the function of which is to lift) and yet one that is not curved or rounded such as would produce suction at the tail to hold the tail of the boat in the water and interfere with the elevation of the tail or breaking of the tail from the water when the boat is used in a hydro-aero-machine and planing at speed with a tendency to rock forward substantially about the rear extremity of its forward hydroplaning surface into a more horizontal position of less resistance to headway. In the present form of the invention as stated, this reverse hydroplane surface is flat.

At the stern 12 of the boat is a suitable water rudder 22, preferably of rigid material carried on the pivoted rudder post 23, and beneath said rudder is preferably a projecting skeg 24 for protecting the same. Mounted above the water rudder and preferably upon the same post 23 therewith is the vertical air rudder 25 of lighter material, such as a canvas covered frame, for steering the machine to the right and left in the air. The air rudder 25 has an extension 26 forward of its pivot to partially balance the wind pressure thereon.

On the tail of the boat is also mounted a stationary vertical fin 27, stationary hori-

zontal fins 28-28, and horizontal rudders 29-29, which are arranged, constructed and controlled as more fully set forth and described in my above-mentioned parent application. The machine is also provided with wing tip pontoons 30-30 and with ailerons 31-31, all arranged, constructed and controlled as more fully described in my said parent application. The arrangement, location, construction and operation of the supporting and controlling air planes and pontoons form no part of my present invention.

It will be seen from the foregoing description of the present embodiment of my invention that boat hulls embodying the preferred form of my invention have a relatively deep broad forward portion with a relatively broad overhanging bow and with an effective hydroplane bottom extending from the nose of the boat downwardly and rearwardly in such manner that if the boat strikes the water at a sharp angle it glides into a more horizontal position, and that the forward hydroplaning bottom of the boat terminates in a step at the intermediate portion of the boat preferably in proximity to a vertical line through the center of gravity of the boat, the hydroplaning bottom being sufficiently broad and effective to comprise the sole supporting surface of the boat when skimming at high speed on the surface of the water, and that the tail portion of the boat is higher than this bottom surface and is of relatively small displacement per unit of length as compared with the forward portion and is provided with an upwardly and rearwardly inclined bottom surface preferably in the form of a reverse hydroplane surface to enable the boat to readily attain speed and break from the water when driven by the aerial propeller. In the usual operation of these boats in connection with hydro-aero-machines, the boat when running at low speed drags downwardly at the tail, and then when the boat attains a high speed, it is adapted to rock forward about the step into a more horizontal position, so that the boat planes along on the surface of the water upon its forward hydroplaning surface with the air planes at a lesser angle of incidence and with its tail in a more elevated position, from which position the boat may be rocked rearwardly again to increase the angle of incidence and enable the machine to readily take the air.

Having thus described my invention, what I claim as new and desire to secure by Letters Patent, is:—

1. In a boat the combination of a relatively deep forward portion having an effective hydroplane bottom beneath the same and extending from the bow downwardly and rearwardly and thence rearwardly

more horizontally and of substantially the full width of the water-submerged sides of the boat, a rearwardly facing step formed in the bottom of the boat and terminating 5 in the bottom of the boat hull having a wide decked over comparatively shallow hydroplaning frontal portion, a relatively deeper intermediate portion, a rearwardly and upwardly inclined tail portion, a transverse bottom 30 edge formed at the juncture of said frontal portion and said tail portion, a cockpit located forwardly of said tail portion and above the deck of said frontal portion, a raised decking extending rearwardly from 35 said cockpit to overlie said edge, and a means erected upon said frontal portion to continue the streamlines of said raised decking forwardly beyond said cockpit and with 40 said frontal portion give to the hull a streamline entry at the bow.

10 to provide a relatively long tapering tail portion, a cockpit formed in the forward portion of the boat, and a deck inclined downwardly and rearwardly from the cockpit toward the stern.

15 2. A boat having a wide comparatively shallow hydroplaning frontal portion, a main decking comprising a depressed portion and constituting the top wall of a pontoon, a rearwardly and upwardly projecting

20 tail carrying a rudder, a seat for an operator located on the depressed portion of the decking of said wide frontal portion, and a false

outer or bow decking covering said frontal portion and of a form to give a stream-line entry thereto. 25

3. In a boat hull having a wide decked over comparatively shallow hydroplaning frontal portion, a relatively deeper intermediate portion, a rearwardly and upwardly inclined tail portion, a transverse bottom 30 edge formed at the juncture of said frontal portion and said tail portion, a cockpit located forwardly of said tail portion and above the deck of said frontal portion, a raised decking extending rearwardly from 35 said cockpit to overlie said edge, and a means erected upon said frontal portion to continue the streamlines of said raised decking forwardly beyond said cockpit and with 40 said frontal portion give to the hull a streamline entry at the bow.

In testimony whereof, I have signed my name to this specification.

GLENN H. CURTISS.
